Inventor:

Gaston Candas,

By his Attorney W. S. Quartron

UNITED STATES PATENT OFFICE.

GASTON CANDAS, OF PARIS, FRANCE.

HINGE FOR JEWELRY.

Application filed March 12, 1926, Serial No. 94,207, and in France January 22, 1926.

This invention relates to hinges, more especially for articles of jewelry, such as bracelets, collars, necklaces and the like, constructed of a plurality of links or plates and has for its particular object the provision of a hinge for such articles which is adapted to effectively hold the links or plates together and when the article is in position on the body of the wearer to substantially close the joint between the two adjoining plates and to minimize the visibility thereof, besides serving to effectively hold the parts together.

It has been customary to provide hinges of various types for connecting the component plates or links of bracelets or like articles of jewelry, but such hinges, in so far as I am aware, did not prevent the penetration of light through the joint between the two adjoining members and have thus rendered such joint readily visible to the eye of an observer, whereas in bracelets embodying my invention this objection is eliminated.

My invention is fully set forth in the following description and drawings forming a part thereof in which latter

Figure 1 is a longitudinal section of one plate of a bracelet carrying one member of my improved hinge and

Fig. 2 is a similar view of an adjoining plate carrying the other member of such hinge;

Fig. 3 is a longitudinal section showing the adjacent parts assembled in an extreme open position and Fig. 4 is a similar view showing the same parts in a closed position as the same would be worn on the arm of a person; and

Fig. 5 is a diagrammatic perspective view of a complete bracelet having two adjoining plates connected by one of my improved hinges.

Referring to the drawings and the construction shown therein, the reference numerals 1, 1' designate two adjacent plates or members of a sectional bracelet, each of which as shown has oblique edges 2, 2' respectively of the same angularity with respect to the outer face a , a' of each plate. The member 1 is provided with one component of a hinge comprising an inner cylindrical sector 3, the outer surface of which

sector corresponds in curvature to a circle described from the nearest point in the edge b , the same being rigidly secured to the inner base of the plate 1. A second cylindrical 55 sector member 4, which is spaced from the first sector member and also has its inner and outer surfaces corresponding to a concentric circle, is also described from the nearest point in the edge b .

An integral lug or stop member 5 is provided on the outer end of the sector 4 which latter sector is in turn rigidly secured, as is the sector 3, by soldering or otherwise to the member 1.

The co-operating member 1' is provided with co-operating arcuate members or sectors of cylinders 6 and 7 respectively, which are adapted to have sliding engagement with the sectors 3 and 4 respectively when the adjacent 70 members 1, 1' are assembled as shown in Fig. 3 and the inner and outer surfaces of the member 6 and the inner surfaces of the member 7 comprise arcs having a radius equal to the distance from such surfaces to the nearest 75 point in the edge c and consequently such faces are concentric with respect to a common center in the edge c whereby when the joint is manipulated the adjacent edges b and c will always remain in contact and prevent the penetration of light therethrough and thus greatly reduce the visibility of the joint between these edges irrespective of whether the parts are in the position shown in Fig. 3 or completely closed as shown in 80 Fig. 4.

Having thus described my invention, what I claim and desire to secure by United States Letters Patent is:

A sectional band of rigid material comprising a plurality of relatively movable substantially rectilinear abutting sections having oblique end faces, means for permitting the band to be opened into a rectilinear line or broken into a polygonal configuration, the 90 said means comprising an apertured sector of a circle secured to one section and projecting from the end thereof an extent substantially equal to about one-half of its total length, the inner face of the portion of such 95 section to which the sector is secured corresponding to a radius of the circle from 100

which such sector is described and the said projecting portion of the sector having an oblique face corresponding to another radius of the same circle but projecting to an angle 5 of the first mentioned radius, said sector being provided with a slot concentric to the circumference of such circle, and the other section having a plurality of concentric arcuate lugs, one of which is adapted to travel 10 in the aforesaid concentric slot and the other of which is adapted to ride on the circum-

ference of the circle of said sector and a stop member projecting from the periphery of said sector and adapted to abut the end of the latter lug when the aforesaid sections are 15 opened so that their outer surfaces are in rectilinear alignment with each other.

Signed at New York, in the county and State of New York, this 11th day of March, 1926.

GASTON CANDAS.
